(57) **CLAIM**

The ornamental design for a portable dental equipment, as shown and described.

DESCRIPTION

FIG. 1 is a perspective view of a portable dental equipment, with the case cover opened;

FIG. 2 is a front view thereof;

FIG. 3 is a rear view thereof;

FIG. 4 is a top plan view thereof;

FIG. 5 is a bottom view thereof;

FIG. 6 is a right side view thereof;

FIG. 7 is a left side view thereof; and,

FIG. 8 is an enlarged view of the control panel thereof.

The broken lines are included for the purpose of illustrating portions of the portable dental equipment that form no part of the claimed design.
